JOHN H. WOODALL, OF WOODLAND, GEORGIA.

PAD FOR FRUIT CONTAINERS.

Application filed May 13, 1926. Serial No. 108,905.

This invention relates to improvements in pads or cushions such as are employed in packing fruit in crates and baskets for shipment. In shipping certain fruits, peaches in 5 crates for an instance, it is an advantage to pack the fruit somewhat tightly in the container to prevent shifting and consequent chafing to the injury of the fruit. In this method of packing it is the practice to fill 10 the container with the fruit and then place over the same a resilient pad, against which is closed and fastened the cover of the container. The cover and pad apply pressure to the fruit and prevent shifting of the same, 15 the pad also prevents contact of the fruit with the under side of the cover and bruising is thereby avoided; also, the top layer of fruit being embedded somewhat in the pad, is held against lateral displacement. 20 As these pads are intended to be use but once, they must be inexpensive as possible; ordinarily they are formed of a cheap casing filled with excelsior.

The fruit so packed is shipped in refrigerator cars in which much moisture is present. In such shipments it has been found 25 that the pads in ordinary use absorb considerable moisture and become soggy so that the excelsior loses its resiliency to such an extent that pressure is no longer exerted on the fruit and the latter is so loosened that it is liable to become injured by subsequent rough handling of the crates. Also, when the pad becomes soggy its contact with the 30 fruit has a tendency to soften the skin. Furthermore, owing to the soggy condition of the pad casing, the fibres of the paper lose their cohesive property and this paper is easily broken, so that in subsequent handling the pad is ruptured with a consequent litter. This litter detracts from the appearance 35 of the fruit when the crate is opened for display by the retailer and must be removed with considerable trouble so that a pleasing showing of the goods can be made. 40 Also, the ruptured pad cannot be used should there be further shipment of the crate and a new pad would be required.

The purpose of the present invention is 45 the production of a pad that is inexpensive

to manufacture and which will avoid the objectionable features of the pads in ordinary use as hereinbefore pointed out. In the instant pad, instead of the absorbent paper heretofore used for the entire casing, waterproof paper is employed in part for the 55 purpose.

In the tests and trials leading up to the present invention much trouble was experienced in adapting the waterproof paper to the purpose. To meet the requirements of low cost it is necessary to use very thin paper, but owing to the flimsy and brittle nature of this paper, it was found that it could not be worked in the forming and cutting machine with the same facility as the stronger absorbent papers ordinarily used.

It may be stated here that in the manufacture of these pads in large quantities a forming machine is used through which are fed the waterproof paper in a continuous web and the excelsior in a continuous bat, the latter being deposited on the former. As the associated materials travel through the forming machine, the sides of the web (the paper being wider than the bat) are gradually folded over the edges of the bat until the folds overlap an intermediate or supplemental reinforcing strip of paper fed onto the top of the bat. During the progress of the material through the forming machine the edge parts of the web folds are pasted to the intermediate strip. When the formed material reaches the rear end of the forming machine, it is cut by a reciprocating blade into sections, each of which is a complete pad except that the ends of the casing are open and these are subsequently closed by folded strips of sealing paper.

It was attempted to make the pad casing entirely of the thin waterproof paper, but difficulty was experienced in pasting the parts together. When the paste was applied and the parts brought together, they did not quickly adhere owing to the non-absorbent property of the paper, for the water in the paste was not absorbed, or but very slowly, and the paste continued in a state of fluidity until the water evaporated.

This slowed the operation of the machine in the formation of the continuous padding, and also in the application of closing strips at the ends of the casing. These difficulties were overcome to a great extent by forming the pad casing in part of ordinary paper. As the latter is much cheaper than the waterproof paper, its use lessened the cost of production. Also this ordinary paper could be used in a much thicker grade so as to strengthen the casing. Furthermore, this ordinary paper is absorbent to a considerable degree and when pasted to the waterproof paper, the former quickly absorbs the water in the paste and thereby hastens the adhesion.

In the accompanying drawings, in which similar reference characters designate corresponding parts:

20 Figure 1 is a plan view of the back of a pad embodying the proposed form of the invention.

25 Figs. 2 and 3 are, respectively, sectional views on the lines 2—2 and 3—3 of Fig. 1.

30 Referring to the drawings, which illustrate the preferred embodiment of the invention, to facilitate the description, the lower or under side of the pad with reference to the position it occupies in the crate will be termed the face and the top or upper side the back of the pad. The face 5 of the pad is formed of a sheet of waterproof paper that extends over the entire face and at its sides it is continued around the sides 35 of the pad to partly overlap, as at 6, the back 7. Extending longitudinally of the back 7 is the reinforcing strip 8 of ordinary tough paper, which extends the entire length of the pad and nearly the entire width. This strip 8 is overlapped at its sides by the extensions 6 of the face sheet, the overlapping parts being pasted together. The ends of the casing are closed by the 45 transverse reinforcing strips 9 folded over the ends and pasted to the face and back. The strips 9 are also of ordinary tough paper.

50 The transverse reinforcing strips 9 close the ends of the casing and also unite the ends of the longitudinal reinforcing strip 8 with the adjacent ends of the waterproof paper. By uniting in this way the waterproof paper with the longitudinal and transverse reinforcing strips, the comparatively 55 frail waterproof paper is held and protected by the much stronger strips. Enclosed within this casing is a bat of excelsior 10, providing the resilient cushion for the pad. It is obvious that other resilient fibrous material, such as cotton, hair and the like may be used for the filling.

60 By experience I have found that it is a great advantage to provide the pad with a waterproof face, the part of the pad that contacts with the fruit, to separate the ex-

celsior from the fruit, for the excelsior is apt to become more or less soggy through absorption of moisture in the refrigerator car. With ordinary paper, which is absorbent to a considerable extent, interposed between the soggy excelsior and the fruit, the paper would also become soggy and its contact with the fruit would have a tendency to soften the skin of the fruit; this would be particularly so should the fruit be fully ripe, or nearly so. It would be an advantage to enclose completely the excelsior packing in a waterproof closure. This would not only prevent the contact of soggy material with the fruit, but the excelsior would be maintained in a comparatively dry condition and would retain its resiliency for a longer period. However, to form the entire casing of waterproof paper, would increase the expense of production somewhat over that of the pad having only its face formed of such material. Furthermore, the cost of production would be increased by the difficulty encountered in pasting together waterproof surfaces.

90 As the pads are intended to be used but once, that is, for a single shipment, their cost must be kept as low as possible. In the cost of material, that of the water-proof paper is the greatest; it is to lessen this expense that the ordinary paper is used for the back of the pad. As the ordinary paper is comparatively cheap, a strong thick paper can be employed for the back of the casing. This paper imparts considerable strength to the casing so that the waterproof paper may be of a very flimsy character; it is desirable to employ the thinnest waterproof paper possible as it is the cheapest. Also, by the use of the ordinary paper in the back insert strip and end closures, through the absorbent property of such paper, the paste sets quicker as the water is absorbed by the paper. In addition, by using the comparatively heavy and tough paper for the back 100 insert strip, an advantage is obtained in cutting the batting into pad sections. In the cutting operation a shearing knife is employed.

105 As the knife descends on the material it effects a pulling or drawing action on the casing that has a tendency to tear the top layer of paper. To offset this tendency the padding, in the preferred form of the invention, is fed to the cutting mechanism so that the back having the tough paper insert is uppermost so as to be engaged first by the descending knife so that when it is drawn and pressed down before the actual cutting takes place, the tough nature of the 115 paper prevents tearing. This tough paper insert also serves to stiffen the completed pad so that it can stand rough handling.

120 What I claim is;

125 A pad for fruit containers comprising a

bat of resilient fibrous material and a casing for the bat consisting of a face part formed of waterproof paper, a back part formed of a longitudinal reinforcing strip of tough paper with its marginal sides overlapped by and adhering to the marginal sides of the waterproof face part, and transverse rein-

forcing strips of tough paper folded over the ends of the casing with the folds of the transverse strips overlapping and adhering ¹⁰ to the marginal ends of the face and back parts of the casing.

In testimony whereof I affix my signature.

JOHN H. WOODALL.
